UNITED STATES PATENT OFFICE

ERIC A. SCOTT, OF CHICAGO, AND GILBERT P. FLEETWOOD, OF JOLIET, ILLINOIS

FIREPLACE CONSTRUCTION

Application filed June 30, 1930. Serial No. 465,028.

This invention relates to means for simplifying and improving the construction of fire places and particularly the smoke chamber or throat portions thereof. Such means comprises in general suitable frame members which are preferably adjustable and detachable for supporting the brick work and also the flue lining during the bricking operation.

The objects of this invention are to provide 10 an improved framework or support which will provide a suitable form for a fireplace smoke chamber or throat section; to provide a form of the character indicated which is constructed of a plurality of sections with 15 means for conveniently connecting the section; to provide a smoke chamber support having reticulated sections or sections having bars for supporting the brickwork and to provide such other improvements in construction and such other advantages as will 20 appear from the following description.

In the accompanying drawing illustrating this invention;

Figure 1 is a front view of a form or frame 25 embodying this invention;

Figure 2 is a plan view showing the front section swung outwardly or in adjusted position;

Figure 3 is a side view; and 30 Figure 4 is a detail of the rear cross bar or connecting member.

As shown in the drawing a frame or form for the smoke chamber comprises the front section 5 having a longitudinal lower bar or strip 6 with a forwardly projecting flange 7. It also has a longitudinal top bar or strip 8 which is connected at the ends to the lower bar by diagonal end strips 9, these being tapered to give the desired shape to the sides of 35 the smoke chamber. The top and bottom bars are also connected by parallel bars 10 thereby forming a substantially rectangular opening at the center of the front frame. The end strips 9 are also connected to the strips or 40 bars 6 and 10 by diagonal bars 11, as shown in Figure 1. The entire frame member is preferably cast so that these bars are formed integrally. The front member is also provided adjacent to the top with outwardly 45 projecting studs or buttons 12 which are also

preferably formed integrally with the section and which provide fastenings for the adjacent frame members.

The end sections 13 of the smoke chamber which are adapted to engage the diagonal bars 9, comprise substantially rectangular frames with diagonal bars or cross pieces 14, as shown in Figures 2 and 3, these frames being duplicates or interchangeable. These end sections have outwardly projecting flanges 15 at their lower edges and lugs or projections 16 extending beyond the flanges. The front edges of the end sections 13 are provided adjacent to the tops with slots or recesses 17 for receiving the fastening buttons 12 whereby 20 these parts are fastened together although permitting adjustment of the front section 5. The end sections are also provided with oppositely disposed slots 18 for receiving fastening lugs or buttons 19 on a cross bar 20, 25 which extends across the back of the chamber and connects the upper ends of the end sections. The upper edges of the bars 9 are preferably offset or provided with flanges 21 which fit against the edges of the end sections 30 when the front section is swung inwardly or 35 to vertical position and which provide supports for the overlying brick when the front section is adjusted to an open position, as shown in Figures 2 and 3. The various bars 40 or strips forming the different sections may be made either plain or ribbed in order to 45 strengthen the same.

In the construction of a fireplace the outer brickwork is usually placed in position prior 50 to finishing the lining or placing the fire brick in position. The end sections 13 are preferably supported on the common brick by means of the projections 16 so that the fire 55 brick may be placed inside of the common brick and will come flush with the inner surface of the smoke chamber. The front section may be swung outwardly or adjusted, as shown in Figure 3, with its lower edge resting on the fireplace damper housing 22, or it 60 may be closed against the side sections if the fireplace is to be of less depth. When in extended position, it will be noted that the outer 65 edge of the flange or projection 21 is in alignment with the outer surface of the adjacent 70

end sections so that bricks placed on the end sections and extending beyond the same will rest against and be supported by such edge or flange.

5 The chimney lining as indicated at 23 rests on the top of the smoke chamber frame and the end sections are covered over with bricks up to such lining, the frame sections serving to support the bricks as they are being applied. The opening through the front section 10 provides access to the lower or inner surfaces of the sections so that the inner surfaces may be pointed up or finished in a convenient manner. After this is done the bricks are applied to the outer surface of the front section being supported in part by the flange 7 to 15 complete the bricking in of the chimney throat. The open-work frames provide means for properly supporting the brick and at the same time are sufficiently light so that they may be conveniently handled and assembled. Furthermore such reticulated or bared sections may be made sufficiently strong 20 of cast iron metal so that they are not apt to crack either in manufacture or in use.

25 Having thus described our invention which, however, we do not wish to limit ourselves to the exact construction herein shown and described except as specified in the following 30 claims. What we claim is:

35 1. A frame or support of the character set forth, having end sections with outwardly projecting lugs at the lower ends thereof, a front section with tapered ends for receiving the end sections, means for pivotally securing the front and end sections together at the top and a bar for securing the rear portions of the end sections together.

40 2. A smoke chamber frame comprising a front section having an outwardly projecting flange along the bottom thereof and having fastening buttons at either side thereof, end sections having outwardly extending projections at the bottoms thereof and having 45 means for receiving said fastening buttons, a cross bar having integrally formed fastening buttons and means at the rear of the end sections for engagement with the fastening buttons on said bar.

50 3. A smoke chamber construction comprising reticulated end sections formed of cast metal and having recesses adjacent to the tops thereof, a front section formed of reticulated cast metal with tapered ends for engagement with the end sections, studs on the front section adjacent to the top for engagement with the recesses in the end sections, and a bar having projections for engagement with the recesses in the end sections at the back 55 thereof.
